UNITED STATES PATENT OFFICE.

SANFORD L. CLUETT, OF HOOSICK FALLS, NEW YORK, ASSIGNOR TO WALTER A. WOOD
MOWING & REAPING MACHINE COMPANY, OF HOOSICK FALLS, NEW YORK, A COR-
PORATION OF NEW YORK.

MOWING-MACHINE.

1,234,528.

Specification of Letters Patent. Patented July 24, 1917.

Application filed May 13, 1914. Serial No. 838,382.

To all whom it may concern:

Be it known that I, SANFORD L. CLUETT, a citizen of the United States, residing at Hoosick Falls, county of Rensselaer, and 5 State of New York, have invented certain new and useful Improvements in Mowing-Machines, of which the following is a specification.

The invention relates to such improvements and consists in the novel construction and combination of parts hereinafter described and subsequently claimed.

Reference may be had to the accompanying drawings, and the reference characters 15 marked thereon, which form part of this specification. Similar characters refer to similar parts in the several figures therein.

Figure 1 of the drawings is a top plan view of a mowing machine embodying my 20 invention.

Fig. 2 is a vertical longitudinal section of the same taken on the broken line 2—2 in Fig. 1.

Certain objects of the invention are to 25 adapt the cutter-bar to more readily pass over ordinary obstructions in its path; and to provide proper friction between the traction wheels and the ground under difficult working conditions.

30 The modern mowing machine to which the invention particularly relates has a laterally projecting cutter-bar pivotally mounted at its inner end upon an axis extending longitudinally of the machine, which permits the 35 bar to be vertically oscillated.

The member upon which the inner end of the cutter-bar is so pivotally mounted is an angular frame formed by the drag-bar which extends transversely of the machine, and 40 the push-bar which extends from the point of junction of one of its ends with one end of the drag-bar, whereat the cutter-bar is pivotally mounted, obliquely rearward, the other ends of said push-bar and drag-bar 45 being pivotally mounted upon the main-frame of the machine on an axis extending longitudinally of the machine.

Both the cutter-bar and the cutter-bar-supporting frame are thus capable of rising 50 and falling movements, which enables the cutting mechanism to adapt itself to inequalities in the ground over which it passes.

In machines of this type as heretofore constructed, the respective axes upon which the

cutter-bar and cutter-bar-supporting frame 55 were so pivotally mounted have extended in substantially horizontal lines longitudinally of the machine; and when the forward movement of the cutter-bar was resisted by an obstruction, such resistance was in lines 60 parallel with said axes.

In carrying out my invention in preferred form, I pivotally mount both the cutter-bar and the cutter-bar-supporting frame upon axes which are inclined upwardly and forwardly longitudinally of the machine. 65

In a machine having said axes so inclined, the rising movement of the cutter-bar, as well as the rising movement of the cutter-bar-supporting frame, is a resultant of an 70 upward movement and more or less rearward movement in accordance with the degree of inclination of the respective axes; and when the cutter-bar meets an obstruction which offers resistance along horizontal 75 lines to the forward movement of the cutter-bar, such resistance tends to force the cutter-bar rearwardly with a resultant tendency to raise the cutter-bar, thus permitting the cutter-bar to ride more freely over such ob- 80 struction.

When the inner end of the cutter-bar or the shoe whereby it is pivotally mounted upon the cutter-bar-supporting frame, meets a similar obstruction, the obstruction tends 85 to force said frame rearwardly with a resultant tendency to raise the frame, which causes the shoe and cutter-bar to more freely ride over such obstruction.

Referring to the drawing wherein the invention is shown in preferred form, 1 represents the main frame of the machine mounted upon traction-wheels, 2.

The cutter-bar-supporting frame comprises the drag-bar, 3, and the push-bar, 4. 95

The drag-bar is pivotally mounted upon the frame at 5, and the push-bar is pivotally mounted upon the frame at 6, the pivotal connection at 5 being at a higher level than the pivotal connection at 6, whereby the 100 cutter-bar-supporting frame is pivotally mounted upon the main-frame, 1, upon an axis extending longitudinally of the machine as shown by the broken line A—A in Fig. 1, which axis is upwardly and forwardly inclined as indicated by the broken line 105 A'—A' in Fig. 2.

Upon the swinging end of the frame

formed by the drag-bar and push-bar is mounted a hanger or yoke, 7, upon the respective arms of which the main shoe, 8, of the cutter-bar is pivotally mounted, at 9 and 5 10, upon an axis which extends longitudinally of the machine, as indicated by the broken line, B—B, in Fig. 1, which axis is upwardly and forwardly inclined, as indicated by the broken line B'—B' in Fig. 2.

10 The convergent ends of the push-bar 4, and the drag-bar 3 are secured in fixed relation to each other by a suitable casting through which the drag-bar 3, projects to form a pivotal connection for the yoke or 15 hanger 7.

A broken-away portion of the cutter-bar is shown at 11, the cutter-bar being fixed upon the main-shoe, 8.

The cutting mechanism is operated by 20 means of a pitman, 12, connected with a crank, 13, on a crank-shaft, 14, which crank-shaft is operated by connections with the neighboring traction-wheel, 2, in the usual manner.

25 The cutter-bar and the cutter-bar-supporting frame can be raised and lowered by hand in the usual manner.

For convenience of illustration, however, I have omitted from the drawings the mechanism 30 for so operating them.

Constructed as shown and as described above, the machine will readily pass over many obstructions, to pass which with a machine made as formerly would require the 35 driver to raise the cutter-bar or the cutter-bar-supporting frame by hand.

I have also ascertained that by upwardly and forwardly inclining the axes of the cutter-bar and the cutter-bar-supporting frame, 40 as above described, I can practically overcome the tendency of the traction-wheels to rise from the ground due to the forward pull of the horses upon the main-frame when the machine is operated in heavy tangled 45 grass which tends to draw the cutter-bar down toward the ground.

Under such conditions in the use of this type of mowing machine as formerly constructed, the forward pull of the horses 50 tended to exert a lifting force upon the traction-wheels, which so reduced the friction between said wheels and the ground that the traction-wheels would become inoper-

ative to drive the cutting-mechanism, and the machine would become stalled.

My invention tends to overcome this loss of friction between the traction-wheels and the ground, and under certain conditions may increase such friction.

What I claim as new and desire to secure 60 by Letters Patent is—

1. In a mowing-machine, and in combination, a main-frame, a cutter-bar-supporting frame pivotally mounted upon the main-frame on an axis extending upwardly and 70 forwardly longitudinally of the machine during its normal operation, and a cutter-bar pivotally mounted upon said cutter-bar-supporting frame upon an axis extending upwardly and forwardly longitudinally of 75 the machine when said cutter-bar is in its normal cutting position.

2. In a mowing-machine, and in combination, a main-frame, a drag-bar pivotally mounted at one end upon the main-frame, a 80 push-bar pivotally mounted at its rear end upon the main-frame in rear of and at a lower level than said pivotally mounted end of the drag-bar and, extending obliquely forward toward the outer end of the drag-bar, a hanger connected at the outer ends of said push-bar and drag-bar, and a cutter-bar having a main-shoe pivotally mounted upon said hanger on an axis extending upwardly and forwardly longitudinally of the 85 machine when said cutter-bar is in its normal cutting position.

3. In a mowing-machine, and in combination, a main-frame, traction-wheels upon which said main-frame is mounted, a cutter-bar-supporting frame pivotally mounted upon said main-frame on an axis extending upwardly and forwardly longitudinally of the machine during its normal operation, a cutter-bar pivotally mounted upon said cutter-bar-supporting frame on an axis extending upwardly and forwardly longitudinally of the machine when said cutter-bar is in its normal cutting position, and traction-wheel-actuated cutting mechanism.

In testimony whereof, I have hereunto set my hand this 4th day of May, 1914.

SANFORD L. CLUETT.
